UNITED STATES PATENT OFFICE.

JOSEPH N. MEYER, OF NEWARK, NEW JERSEY, ASSIGNOR OF ONE-HALF
TO THOMAS J. RYER, OF SAME PLACE.

BOWLING-ALLEY.

SPECIFICATION forming part of Letters Patent No. 566,273, dated August 18, 1896.

Application filed October 19, 1895. Serial No. 566,269. (No model.)

To all whom it may concern:

Be it known that I, JOSEPH N. MEYER, a citizen of the United States, residing at Newark, in the county of Essex and State of New Jersey, have invented certain new and useful Improvements in Bowling-Alleys; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

15 The objects of this invention are to facilitate and render more exact the adjustment of the pins upon the alley preparatory to bowling the balls, to avoid damaging the pins by forming therein holes for guide-pins, &c., 20 and to secure other advantages and results, some of which will be referred to hereinafter in connection with the description of the working parts.

The invention consists in the improved 25 bowling-alley and in the combinations and arrangements of parts, all substantially as will be hereinafter set forth, and finally embraced in the clauses of the claim.

Referring to the accompanying drawings, 30 in which like letters and figures indicate corresponding parts in each of the several views, Figure 1 is a plan of a portion of a bowling-alley. Fig. 2 is a longitudinal vertical section of the same. Fig. 3 is an enlarged sectional 35 detail showing the relation and operation of certain of the parts more clearly. Fig. 4 is a detail elevation of a pin-support, and Fig. 5 is a detail plan showing certain connections more clearly.

40 In said drawings, *a* indicates a portion of a bowling-alley of any ordinary construction, and *b* is an end flooring, which is perforated to receive adjustable supports on which the pins are seated, said end flooring lying at the 45 end of the alley opposite that at which the bowlers stand and closely adjacent to the "pit" *b'*, into which the pins are ordinarily thrown when hit by the balls. Said flooring *b* is preferably hinged, as at *b''*, to the body 50 of the alley, as indicated in Fig. 1, and is

thus adapted to be raised, so that access to certain mechanisms hereinafter referred to may be conveniently gained. A suitable catch *b'''*, Figs. 1 and 2, may be employed at the end opposite the hinges to hold the said 55 end flooring down in place.

At suitable points in the flooring *b* corresponding with the positions at which the pins *A* are usually placed the said flooring is perforated, as before indicated, and in the perforations are inserted pin-sockets *c*, the recesses at the upper ends of which correspond in diameter more or less closely with the diameter of the lower ends of the pins *A*, so that when said pins *A* are arranged in said 65 sockets said pins will be in proper lateral relations to one another to receive the balls rolled forward by the player. Said pin-sockets are flanged at *c'*, and may be seated on adjusting-screws *c''* so as to bring the upper 70 surfaces of the sockets flush with the floor *b* and to admit of an easy lowering of the sockets as the floor wears away. The sockets are held to said floor *b* by nuts *e*, the sockets being suitably threaded, as at *c'''*, Fig. 3, to receive 75 said nuts.

Below the threads *c'''* the sockets are reduced in diameter, forming extensions *c''''*, on which brackets *f* are secured. These last have arms *f'*, which are turned downward and 80 provide fulcrumal bearings for bell-cranks or levers *g*, adapted to operate pin-supports *d*, having their upper ends arranged within the sockets, so as to raise or lower said upper ends to or from points flush with the surface 85 of the floor. Each of the said pin-supports has a shank *d'* extending downward from the tablet *d''* on which the pin *A* is held, which shank slides vertically in a central perforation *c''''* of the socket *c*, as shown more clearly 90 in Fig. 3.

The tablets *d''* preferably rest upon springs *h*, arranged within the sockets, which springs serve to hold the tablets up flush with the top of the floor. Undue elevation is prevented by stop-nuts *i*, arranged upon the threaded shanks *d'*, which nuts, in the upward movements of the shanks, engage the lower ends of the sockets *c* or the brackets *f* thereon, and thus prevent further vertical 95 100

movement upward. The nuts *i* are preferably locked, so as to prevent displacement due to the operation of parts.

The lower ends of the shanks *d'* are vertically slotted to receive the arms *g'* of the levers *g*, the shanks being provided, preferably, with rollers *j* to secure an easy movement of said arms in connection with said shank. Other arms, *g''*, of the levers *g* are adjustably coupled, by means of coupling-bolts *k*, to transverse shafts *l* and other connections, whereby all the pin-supports *d* of the group can be operated simultaneously and together when manipulated by the pin-boy or attendant in charge. This simultaneous operation is secured by means of a cam, eccentric, or hand-lever *m*, fulcrumed at *n* at the rear of the alley, where it will be out of the way of the balls. Said hand-lever *m* bears on a plunger *o*, working in a socket or receptacle *p*, arranged in connection with the rear board *q* of the alley, walling the pit, and thus as the hand-lever is turned on its pivot or fulcrum said plunger is moved longitudinally. The plunger, at its end opposite that engaged by the hand-lever, impinges upon a lever *r*, fulcrumed at *s* on a bracket *s'* on the inner side of said board *q*. Said lever *r* in turn engages a slotted yoke *t*, entering the slot thereof, as in Fig. 3, and gives to said yoke a horizontal movement. Said yoke is pivoted to levers *u*, fulcrumed at *v* to links *w* of brackets *3*, said levers *u* carrying the first of a series of shafts *l*, before referred to. The levers *u* serve to reduce the movement imparted by the lever *r*, as will be understood.

The transverse shafts *l* are all coupled together by couplings *4*, which are adjustable so as to readily and easily increase or reduce the distance between said shafts or otherwise modify their relation to one another. Said shafts *l* vary in length, the ones nearest the end board *q* of the alley being in a pair, so as to receive the couplings of four pin-supports, the second one being of a length to receive three sets of couplings, the next shaft two, and the fourth one, as will be understood upon reference to Fig. 1.

A spring *6*, attached to the under side of the floor *b* and to the connected shafts *l*, serves to draw said parts horizontally, so as to throw the supports upward.

In operating the parts thus described the handle of the cam or lever *m* is raised and the plunger *o* thrown horizontally inward against the lever *r*. This movement throws the levers *p* and *u*, so that the several shafts *l* and coupling-bolts *k* draw the arms *j'* of the levers *g* downward, and with them the pin-supports *d*. The upper extremities of said pin-supports are thus lowered below the flush-line of the floor *b*, and cup-like receptacles or recesses are formed, into which the pins *A* may be inserted with ease, facility, and with exactness of position. The pins being inserted by the attendant, the hand-lever is re-

versed in position and the train of parts will be given reverse movements.

In connection with the fulcrum shaft or pin *n* of the hand-lever I employ a train of mechanisms for operating a signal to indicate to the players, when the signal is in a position expressing "danger," that the pin-supports are in their lowered positions and that the alley is not yet ready for bowling, and when in a "safety" position that the said supports are flush with the floor and the pins are ready to be played upon. Of said train of mechanisms, 8, Fig. 1, indicates a shaft adapted to make a quarter-turn with the hand-lever, and having a cog-wheel *9*, which engages a rack 10 on a shaft 11, arranged at one side of the alley and preferably within a box-like partition 12, separating one alley from another. Said shaft 11 is preferably in sections held together by a turnbuckle 13, by means of which the parts may be adjusted.

At the opposite end of the shaft 11 from the rack 10 is another rack 14, which meshes with a cog-wheel 15 on a vertical shaft 16, carrying at its upper end a signal-arm 17. The parts are so adjusted and related as that when the hand-lever is raised and the pin-support lowered the signal-arm 17 will be thrown transversely across the alley, as shown in Fig. 2 and in outline in Fig. 1, so as to be seen by the players and be understood by them as indicating the fact that the alley is not in condition to be bowled over. When, however, the pins are all in position and the hand-lever is lowered and the pin-supports and pins are raised, then said signal-arm will be turned so as to lie parallel with the alley, and thus indicate that the pins are ready for a play.

Having thus described the invention, what I claim as new is—

1. In a bowling-alley, the combination with the perforated flooring of a group of vertically-movable flat supporting-tablets having shanks *d'*, extending below said flooring, bell-crank levers *g*, engaging said shanks, and a hand-lever and connections operating said bell-crank levers to raise or lower said tablets, substantially as and for the purposes set forth.

2. In a bowling-alley, the combination with the perforated flooring *b*, of sockets *c*, each having an enlarged recess at the upper end and a smaller passage *c'''*, at the lower end, pin-supports having tablet-forming flanges at the upper ends, working in said enlarged recesses and shanks, *d'*, working in said passages, means for holding the sockets rigidly in said flooring, and means for operating said pin-supports whereby they are lowered beneath the flooring to form pin-receptacles and raised to points flush with the flooring to provide a smooth bowling-surface, substantially as set forth.

3. In a bowling-alley, the combination with the perforated flooring *b*, of sockets *c*, each having an enlarged recess at the upper end,

a small shank-passage at the lower end, and an extension beneath the flooring to receive brackets *f*, means for holding said sockets to the flooring, pin-supports working in said 5 sockets, brackets *f*, secured upon the said extensions, bell-cranks fulcrumed in said brackets and operating said pin-supports, and means for operating said bell-cranks, substantially as set forth.

10 4. In a bowling-alley, the combination with the perforated flooring *b*, of sockets *c*, brackets *f*, secured upon the lower ends of said sockets, supporting-tablets with their shanks working in said sockets, springs *h*, limiting-nuts *i*, and means for operating said tablets, substantially as set forth.

15 5. In a bowling-alley, the combination of sockets *c*, flanged pin-supports arranged in said sockets, springs *h*, arranged in said sockets beneath the flanges of said supports, for raising said supports, stop-nuts for limiting the upward movement of said supports, brackets *f*, bell-cranks *g*, and levers and connections of said bell-cranks with a single hand-lever, whereby said bell-cranks are all oper- 20

25

ated simultaneously and said hand-lever, substantially as set forth.

6. In a bowling-alley, the combination with sockets *c*, flanged pin-supports arranged in said sockets, springs *h*, arranged in said sockets beneath the flanges of said supports, stop-nuts, brackets *f*, bell-cranks *g*, levers and a hand device for operating the same, rods *l*, and connections, all arranged and operating, substantially as and for the purposes set forth. 30

7. In a bowling-alley, the combination with the perforated flooring, of flanged pin-supports, resting on springs and normally held flush with said flooring thereby, said springs and means for lowering said supports below 40 the flush-line of the flooring, substantially as set forth.

In testimony that I claim the foregoing I have hereunto set my hand this 6th day of September, 1895.

JOSEPH N. MEYER.
